UNITED STATES PATENT OFFICE.

EDWARD HIRAM TAYLOR, OF ATLANTA, GEORGIA.

HAIR-IRONING COMB.

1,002,942.

Specification of Letters Patent. Patented Sept. 12, 1911.

Application filed August 29, 1910. Serial No. 579,420.

To all whom it may concern:

Be it known that I, EDWARD H. TAYLOR, a citizen of the United States, residing at Atlanta, in the county of Fulton and State 5 of Georgia, have invented new and useful Improvements in Hair-Ironing Combs, of which the following is a specification.

My invention relates to means for straightening hair by pressing it between 10 heated ironing surfaces.

While particularly designed for the purpose of straightening hair, my invention is also adapted by a slight change in construction, to be used to curl the hair.

15 The principal difficulty in straightening hair, particularly when closely curled, lies in the fact that such hair is usually short and it must be brought into contact with heated surfaces and pressed against or between such surfaces. According to my present invention, the hair, after being separated by a comb, passes between heated ironing surfaces or teeth arranged in two sets which are relatively movable so that 20 the teeth of one set can be forced against the teeth of the other set with which they alternate, to press and iron the hair, as it is drawn between them. These teeth are given flat contacting surfaces when it is desired to straighten the hair and are given 25 grooved or waved contacting surfaces when it is desired to use the device as a means for curling hair. The comb and ironing teeth are preferably mounted on a metal 30 base to which a suitable handle is attached and which is of such a character as to retain and radiate the heat to the ironing teeth. If desired other means may be employed to heat the teeth.

40 My invention comprises the details of construction and arrangement of parts hereinafter described and claimed, reference being had to the accompanying drawings, in which:—

45 Figure 1 is a perspective view of the comb complete with the outer casing broken away. Fig. 2 is a detail view of the slide carrying the movable ironing teeth. Fig. 3 is a detail view of the frame carrying the fixed ironing teeth. Fig. 4 is a vertical cross sectional view of Fig. 1. Fig. 5 is a view showing a modified construction of the ironing teeth as designed for curling hair.

50 Similar reference numerals refer to similar parts throughout the drawings.

According to the preferred embodiment

of my invention, I provide a handle 1 having a metal shank 2 which is threaded and screwed into one end of a metal block 3, which is elongated and substantially rectangular in cross section. This block 3 is longitudinally channelled to provide the spaced parallel side walls 4 which terminate at offset shoulders 5 between which is formed a bottom groove 6. A metallic comb is attached to one side of the block 3 by screws or rivets 7 which pass through its base 8. The comb teeth 9 are formed integral with the base 8 and project above the upper surface of the block 3. A slide 10, carrying 70 a series of ironing members or teeth 11, rests upon the shoulders 5 and is provided with a longitudinal tongue 12 which works in the groove 6. The groove and tongue may be dispensed with if desired and the 75 slide left with a flat bottom surface which rests upon the bottom of the channel. The slide 10 is longer than the block 3 and is provided at its free end adjacent to the handle, with a pin or stud 13 to which a 80 link 14 is pivotally connected, the outer end of the link being pivotally connected to a pin 15 mounted at one end of a lever 16 which near its center is pivoted upon a pin 17 fastened to the handle 1. This lever 16 85 has a handle 18 which is arranged so as to be grasped by the fingers of the hand while holding the handle 1, and to be drawn toward that handle when it is desired to operate the slide 10. A spring 19 engages 90 the outer end of the lever 16 near the pin 15 and urges the slide toward the handle. This spring, after being coiled about the pin 17 under the handle 18, is fastened at its outer end 20 to the handle 1 preferably 95 by having that end bent inwardly and inserted in a small hole bored into the handle to receive it.

A fixed frame 21 is secured by set screws 22 in the upper end of the channel, as 100 shown in Fig. 1. This frame is provided with a series of ironing teeth 23, similar to teeth 11. These teeth 23 are set at intervals across a longitudinal groove 24 in the frame. The teeth 11, as shown in Fig. 1, project 105 up through this groove 24 and extend to a point level with the tops of the teeth 23 and alternate with them.

In operation, the device is heated in any suitable manner, either by inserting block 3 110 in a heating flame or an electric heater, or by having any standard form of heater at-

tached, the same not being shown as it forms no part of my present invention. After being thus heated, the device is inverted from the position shown in Fig. 1, and the teeth 9 of the comb are first drawn through the hair to be treated to separate the same and guide it between the pairs of teeth 11 and 23 which stand normally in pairs as shown in said figure. When this has been done the handle 18 is drawn inwardly toward the handle 1 and the slide 10 forced inwardly so that its several teeth 11 shift to the left from the position shown in Fig. 1 and press against the right hand faces of the teeth 23 thus pressing the hair between the hot flat surfaces. The device is then moved so that the hair is gradually drawn between the hot pressing surfaces which effectively straighten it.

To increase the ornamental appearance of the comb I may provide an outer casing 25 which incloses the sides of the block 3 and is provided with a longitudinal slot through which the teeth 11 and 23 project.

To minimize the amount of heat that will be radiated to the teeth 9 of the comb, I provide a longitudinal channel or groove 26 in the side wall of the block 3 opposite the point where the screws 7 pass through the base 8 of the comb.

When it is desired to use the device as a means for curling hair, I make the teeth as shown in Fig. 5, giving them a wider ironing or heating surface and making them grooved or waved in cross section so that, when the hair is pressed between such heated surfaces, it will be waved or curled.

Having thus described my invention, what I claim as new and desire to secure by Letters Patent, is:—

1. In a device of the character described, a heating block, fixed ironing teeth carried by said block, a slide mounted on said block and carrying ironing teeth which alternate with said fixed teeth, and means to force said sets of teeth together, substantially as described.

2. In a device of the character described, the combination with a comb and a heat radiating member, of two sets of alining ironing members, the members of each set being mounted on said heat radiating member and being alternately placed and relatively movable on said member to engage with and be disengaged from each other, substantially as and for the purposes described.

3. In a device of the character described, a heat radiating member, a handle therefor, a set of fixed ironing teeth detachably mounted in said member, a slide carrying movable ironing teeth which alternate with

the fixed teeth, and means to move said slide to press the side face of each movable tooth against the adjacent side face of a fixed tooth, in combination with a comb having teeth parallel with and adjacent to said ironing teeth.

4. In a device of the character described, a metal block having a handle connected at one end thereof and which is longitudinally channeled, a slide which is seated in said channel and movable therein, ironing teeth on said slide projecting above the open channel in the block, a frame fixed in the channel in said block above said slide, said frame having openings through which the teeth on the slide project, ironing teeth on said frame arranged so as to alternate with the slide teeth with which they coöperate, and means attached to the handle for actuating said slide to press said coöperating teeth together, substantially as described.

5. In a device of the character described, the combination with the block of two sets of coöperating ironing teeth, one set alternating with and being movable relatively to the other, and a comb for guiding the hair between said ironing teeth, said comb having a metal base which is connected to said device at one side, said block being grooved longitudinally opposite the point of attachment of said base of the comb, as and for the purposes described.

6. In a device of the character described, the combination of a metal block, a handle connected to said block, two sets of ironing teeth mounted on said block, the one set of teeth being fixed to the block, a support for the other set of teeth which is movably mounted on said block, a casing surrounding the block and tooth support, actuating means to adjust said movable support, and a comb attached to the side of the casing, substantially as described.

7. In a device of the character described, a metal block, a set of fixed ironing teeth carried by said block, a slide and a set of ironing teeth carried thereby which coöperate with said fixed teeth with which they alternate, a link pivotally connected to said slide, a handle for the device, a lever pivoted to said handle and connected at one end to said link, and spring means engaging said lever and tending to urge same away from said handle, substantially as described.

In testimony whereof I have hereunto set my hand in presence of two subscribing witnesses.

EDWARD HIRAM TAYLOR.
